DEVICE FOR SORTING DATA

Filed July 20, 1929

UNITED STATES PATENT OFFICE

ALFRED E. SHAFFER, OF CAMBRIDGE, MASSACHUSETTS

DEVICE FOR SORTING DATA

Application filed July 20, 1929. Serial No. 379,778.

The principal object of my invention is to provide a simple and convenient device having one or more compartments or containers into which data of an accounting or other nature may be sorted, as, for example, the detachable coupons of gas, electric or telephone bills.

A feature of my invention is a plurality of flaps spaced to form compartments and preferably I provide means for holding adjacent flaps in position to receive the proper data.

Another feature is the hinging of each flap so that its free end may take a position at one side or the other of its hinge.

Other features will be pointed out below.

In the drawing

Figure 1 is an elevation of a device embodying my invention;

Figure 2 is a section on line 2—2 of Figure 1;

Figure 3 is a section on line 3—3 of Figure 1;

Figure 4 is a section similar to that of Figure 3 but having one of the hinged members in a different position; and

Figure 5 is a fragmentary section on a larger scale and described below.

The support 1 may be of wood or other suitable material and to one side of it is hinged a retaining member having, as shown in Figures 1 to 4, a portion 2 at a right-angle to the support and another portion 3 extending inwardly and parallel to the support. At the other side of the support 1 is hinged member 4.

Flaps 5 of cardboard or other suitable material are hinged or pivoted to the support 1 and as a means of hinging I show, in Figures 2 and 5, a plurality of tapes, each tape being between adjacent flaps and each having a portion 6 glued to the support, a portion 7 glued to one flap and a portion 8 glued to the adjacent flap. The portions 6 are so spaced that when the flaps are in the position shown in Figure 2 there will be substantial space between adjacent flaps so as to provide compartments to receive desired data 9 in the form of paper slips or in other forms. The uppermost tape is spaced from the top of the support a distance about equal to the length

of the top flap and the lowermost tape is similarly spaced from the bottom of the support so that when the end flaps are brought to a position approximating parallelism with the support, as shown in dotted lines in Figures 2 and 4, there will be a support for them.

The device is to be used primarily with the support in a vertical position and it may be so hung by a picture cord or in any other suitable way. When the support is so placed vertically the flaps are arranged with their free ends higher than their pivots and they tend to swing downwardly on their hinges but this tendency is resisted by portion 3 which is to be swung into the position shown in the drawing, and in this position any data inserted between adjacent flaps will be prevented from slipping out to the left in Figure 1. Member 4 may be swung to the position of Figure 3 where it will prevent data from slipping out to the right or it may be swung further inwardly to the position of Figure 4 in which position it not only prevents said slipping but also has a function of resisting the tendency of the flaps to swing downwardly.

If desired the inner face 10 of member 4 may have suitable indicia relating to corresponding indicia on the flaps and in such case member 4 may be moved into the plane of the support 1 so that its indicia may be readily visible.

When the device is to be removed from its vertical position the flaps may be pressed upwardly into substantial parallelism with support 1 as shown in dotted lines in Figure 4, the uppermost card being supported by the upper part of the support, and members 3 and 4 will be folded inwardly, as shown in dotted lines in Figure 4, to hold the flaps pressed upwardly and I provide a hook 11 on member 3 to engage an eye 12 on member 4 to lock members 3 and 4 in their inwardly folded position. When so locked the device may be moved about without disarrangement or loss of data.

Another use of my device is to make provision for ready tabulation of the data in the several compartments and when the device is to be so used the support will be laid

horizontally on a table or elsewhere and the members 3 and 4 will be unlocked and turned back and it is convenient now to have nearest to the user that portion of the support shown at the top in Figure 2. The flaps may now be swung on their pivots into the position shown dotted in Figure 2, the lowermost flap of that figure having available support in the lower part of support 1. In this position the data in the compartment which was formed by the top card and the support will be available for tabulation and removal whereupon the top flap will be swung toward the upper part of the support leaving the data in the compartment formed by the two topmost flaps available for tabulation and removal and so on for the other compartments. Or when the support is horizontal the lowest flap only may be swung to the dotted line position of Figure 2 leaving the data in the compartment formed by the two lowest flaps available for tabulation and removal and then the flap next to the lowest may be swung to said dotted line position for tabulation and removal of the data in the next compartment and so on.

A sufficient indexing surface is provided for each flap one above the other and, as above explained, either the front or rear face of each flap may be exposed. The flaps may be numbered or lettered as desired, said numbers or letters to run from top to bottom, and the same numbers or letters may appear on the reverse side of the flaps so that when the compartments are sufficiently full and the support put in horizontal position and turned about, as above described, the data in the top compartment of Figure 2 will be nearest the user and be to his convenience in tabulating the data.

In some cases I prefer to hold portion 3 in the position of Figures 2 and 3 by means of hooks 13 on portion 3 engaging corresponding eyes 14 on support 1 as shown in Figure 2, this holding being in addition to the friction of the hinges which connect support 1 and portion 2.

What I claim is:

50 1. A device of the character described comprising a vertical support; a plurality of flaps hinged to the support, each flap being adapted to swing from a position with its free end higher than its pivot to a position with its free end lower than its pivot; and a member hinged to the support to hold the flaps with their free ends higher than their pivots.

55 2. A device of the character described comprising a vertical support; a plurality of flaps hinged to the support, each flap being adapted to swing from a position with its free end higher than its pivot to a position with its free end lower than its pivot; and a member hinged to the support to hold the

flaps with their free ends higher than their pivots, said member being located to prevent displacement at one side of the flaps of data sheets between the flaps; and another member hinged to the support and located 70 to prevent displacement of said data sheets at the other side of the flaps.

3. A device of the character described comprising a support; a plurality of flaps hinged to the support; members hinged to the support and adapted to prevent sidewise displacement of data sheets between the flaps; and means to lock said members together. 75
